UNITED STATES PATENT OFFICE.

HARRY EHLIG, OF PEARL RIVER, NEW YORK, ASSIGNOR TO DEXTER FOLDER COMPANY, OF PEARL RIVER, NEW YORK, A CORPORATION OF NEW YORK.

COUNTER-OPERATING ATTACHMENT.

1,206,825.

Specification of Letters Patent.

Patented Dec. 5, 1916.

Application filed January 18, 1915. Serial No. 2,897.

To all whom it may concern:

Be it known that I, HARRY EHLIG, a citizen of the United States, and a resident of Pearl River, county of Rockland, and State 5 of New York, have invented certain new and useful Improvements in Counter-Operating Attachments, of which the following is a specification.

The purpose of the present invention is 10 to provide a simple and effective attachment for paper handling machinery for operating the ordinary counter to cause the counter to accurately register the number of articles passed through and operated 15 upon by the machine. In producing the mechanism for this purpose I have devised a counter operating attachment which is operated by a part of the machine to which it is applied and automatically controlled 20 by a detecting device which indicates the presence or absence of the article being operated upon, and by such detection determines whether the counter shall operate.

While my invention may be applied to 25 any machine arranged to operate upon the products passed through it, I have chosen for the purpose of illustration, the application of my invention to a paper folding machine in which an ordinary counting device is arranged to be actuated by the paper 30 folding knife. An arm connected with the operating device of the counter is held normally disengaged from a part carried by the folding knife and is intermittently 35 thrown into operative engagement with said part by the operating attachment; a spring actuated member is connected with said arm and held against action by its engagement with the folding knife so that 40 when the knife moves in its folding operation the counter operating arm is pulled over into the path of the operating part upon the knife to cause the operation of the counter; a sheet detecting member presented above the path of sheets is also connected with said spring actuated member 45 so as to be lowered into engagement with a sheet at each operation of the knife, said detecting member having a lost motion connection with said spring actuated member 50 so as to permit the detector to stop when it engages a sheet and allow the continued movement of the spring actuated member, which movement throws the counter arm

into the path of the operating part of the 55 knife and slightly raises the detector from its engagement with the sheet. A stop arm carried by the detector member rests beneath the spring actuated member when the detector moves beyond its normal position in the absence of a sheet, thereby arresting the spring actuated member in position to hold the counter operating arm in disengaged position so as not to operate 60 the counter when a sheet is absent.

In order that my invention may be fully understood, I will first describe the same with reference to the accompanying drawings and afterward point out the novelty more particularly in the annexed claims.

In said drawings.—Figure 1 is a detail, transverse, sectional elevation of a paper folding machine, showing my improved counter operating attachment applied thereto. Fig. 2 is a plan view of the same. Fig. 75 3 is a side view of the same. Fig. 4 is a view similar to Fig. 1, showing the essential parts of the mechanism in shifted position.

1 is part of the frame of an ordinary folding machine, 2—2 are folding rollers 80 and 3 is the folding knife operated in the usual manner.

5 is a bracket secured upon the frame 1 and supporting a counter 6 of any ordinary construction. In the particular counter shown an operating lever 7 projects from one end. The operation of this counter is by moving the lever 7 downwardly and back one stroke.

Pivoted at 10 to the outer end of the 90 counter operating lever 7 is a depending actuating arm 11 having inwardly presented hook 12 formed on its lower end. This hook arm or counter-actuating member 11 is normally presented to one side of 95 a finger 15, secured at 16 to one end of the folding knife 3, as shown best in Fig. 1 of the drawings. In the operation of the device the hook arm 11 is drawn toward the finger 15 to present the hook 12 beneath 100 finger 15 as the knife 3 moves downwardly in the folding operation.

20 is an upright bracket secured at 21 to one of the cross bars 22 of the folding machine at a point preferably adjacent to the 105 longitudinal center of the machine. Pivotedly mounted at 25 upon the bracket 20 is a bell crank arm 26 engaged by a spring

27 which is coiled around the pivot 25 and has one end secured to the bracket at 28 and the other end engaged with one arm of the bell crank 26 to give the bell crank 26 a spring 5 tendency to rotate on its pivot to the right, in Fig. 1. The upper arm 26^a of bell crank 26 has pivoted to it at 30 a pitman 31 which is pivoted at its outer end 32 to the hook arm 11, so that all movements of the bell 10 crank 26 are transmitted to the hook arm 11. Secured to the horizontal arm 26^b of bell crank 26 is an upwardly projecting hook shaped finger 35 whose upper hook end rests upon the upper edge of the folding knife 3 15 and by its engagement therewith normally prevents the movement of the rock arm 26 and parts attached to it, but allows the movement of such parts when the folding knife operates. Pivoted at 40 to the horizontal extension 20^a of bracket 20, is a sheet detecting finger 45 which has an angular forwardly presented sheet engaging blade 46 with an upwardly bent end 46^a presented toward the advancing sheets as they 25 are led into the folding machine. This sheet detecting finger 45 has connected with it a rock arm 47 carrying at its ends a pin 48 which engages the slot 49 of the link 50 pivoted at 52 to the arm 26^b of the bell crank 30 26. The detecting finger 45 also carries an upwardly presented stop arm 55 which under certain circumstances is adapted to rest beneath the shoulder 26^c of the arm 26^b to limit the movement of bell crank 26 and 35 parts connected therewith.

The operation of the device will be understood from the following explanation: A sheet fed into the folding machine passes in position above the folding rollers 2 and 40 is supported by the ordinary bars and slats while it is registered, preparatory to the folding operation. In the machine shown the paper rests above the bars indicated at 1^x in Fig. 1, and the counter operating attachment is in the position shown in this figure at the start of the folding operation. As the folding knife 3 moves downwardly toward the paper, the sheet detecting finger 45 will be lowered with the other parts until 45 the blade 46 rests upon the sheet, which will arrest the movement of the detector 45 and stop arm 55. The sheet being in position, the blade continues to move downwardly into engagement with the sheet and its continued movement permits the continued movement of the bell crank 26 which moves the hook arm 11 over to the right until the hook 12 is in the path of the finger 15, so that the completion of the downward 50 stroke of the knife will register one count upon the counter 6. In this final movement of the parts the slotted link 50 moves upon the pin 48 and the extreme end 26^c (see Fig. 1) of bell crank arm 65 26^b acts upon the cam face 55^a of stop

arm 55 to slightly raise the detector from its engagement with the sheet and free the sheet as it is struck through the folding rollers by the knife. This operation takes place every time a sheet is folded in the machine. If a sheet is missed, the detector arm 45 moving down detects the absence of the sheet and by its extreme downward motion places the stop arm 55 beneath the shoulder 26^c which limits the movement of bell crank 26, so that the hook arm 11 is not pulled inwardly far enough to engage the finger 15 of the knife. In this operation with a sheet missing, the folding knife goes through its regular operation but the counter is not operated. With this simple and effective mechanism the final amount registered by the counter will be the accurate number of sheets actually passed through the folding machine.

My improved counter operating mechanism has been designed particularly as an attachment for paper handling machinery, but I would have it understood that I do not limit my invention to its particular application since it can readily be applied, without essential changes, to any machine through which articles in course of manufacture or treatment are passed and are operated upon by the machine for any purpose.

I claim:—

1. The combination with a machine and a counting device having a member suitably mounted to be moved into and out of position to be operated by a part of said machine, of means for moving said member, and a stop movable into and out of position to block the movement of said member-moving means, said stop being suitably mounted to be held out of position in which it blocks the movement of said member-moving means, by the presence of an article fed by said machine.

2. The combination with a machine for operating upon articles passing through it, and a counting device adapted to be operated by said machine, said machine and counting device having parts movable into and out of position to engage each other, of means for moving one of said parts to adapt the moving part of the machine to drive said counting device, and a member arranged to be operated by said articles and adapted to arrest the operation of said means.

3. The combination with a machine, and a counting device therefor, of a counter-actuating arm adapted to be moved into and out of the path of a moving part of said machine, a spring-actuated operating arm connected with said counter-actuating arm, an operative connection between said operating arm and a moving part of said machine, a detector arm having lost-motion connection with said operating arm, and a stop arm con-

nected with said detector arm and adapted to be moved thereby into engagement with said operating arm to arrest its movement.

4. A counter-operating attachment for 5 machinery comprising a supporting member adapted to be attached to a machine, an operating member movably mounted upon said supporting member and adapted to be operated by a moving part of the machine 10 to which it is applied, a counter-actuating member connected with said operating member and adapted to be shifted thereby into and out of position to be engaged by a moving part of the machine, a detector member 15 having operative connection with said operating member, and means controlled by said detector member for arresting the operation of said operating member.

5. A counter-operating attachment for 10 machinery comprising a supporting member adapted to be attached to a machine, a spring-actuated lever movably mounted upon said supporting member and adapted to be operated by a moving part of the machine 25 to which it is applied, a counter-operating hook-arm connected with said spring-actuated lever and adapted to be shifted thereby into and out of position to be engaged by a moving part of the machine, a 30 detector member having operative connection with said spring-actuated lever, and means controlled by said detector member for arresting the operation of said spring-actuated lever.

35 6. A counter-operating attachment for machinery comprising a supporting member adapted to be attached to a machine, a spring actuated bell crank lever pivotally mounted upon said supporting member and 40 adapted to be operated by a moving part of the machine to which it is applied, a counter-operating member connected with said spring-actuated bell crank lever and adapted to be shifted thereby into and out of position 45 to be engaged by a moving part of the machine, a detector member having operative connection with said spring-actuated bell crank lever, and a stop arm controlled by 50 said detector member for arresting the operation of said spring-actuated bell crank lever.

7. A counter-operating attachment for 55 folding machines, comprising a supporting member for attachment to the machine, a spring actuated lever pivoted to said supporting member adapted to engage the knife of the folding machine and move with it, a hook arm adapted to be connected with the operating member of a counter and movable 60 into and out of the path of a part carried by

said knife, a connection between said lever and said arm, a detector member movable across the plane of sheets, a lost motion connection between said lever and said detector member, and a stop arm carried by 65 said detector member and adapted to engage said lever to arrest its movement and prevent the operation of the counter.

8. A counter operating attachment for a machine designed to operate upon articles 70 passing through it, comprising a supporting member adapted to be attached to the machine, a counter actuating member adapted to be moved into and out of the path of a moving part of the said machine, an operating member 75 mounted upon said supporting member actuated by a part of said machine and connected with said counter actuating member, an article detector operated by the said operating member and movable 80 thereby into and out of the path of the articles passing through said machine, means controlled by said detector for arresting said operating lever, and for disengaging said detector from an article after its detecting 85 action.

9. The combination with a machine designed to operate upon sheets passing through it, and a counting device therefor, of an actuating member connected with said 90 counting device and adapted to be moved into and out of the path of a moving part of said machine, an operating member actuated by the machine and connected with said counter actuating member, a sheet detecting 95 member, means controlled by said detecting member for arresting said operating member, and for disengaging the detecting member from a sheet after the detecting operation. 100

10. The combination with a machine designed to operate upon sheets passing through it, and a counting device therefor, of an actuating member connected with said counting device and adapted to be moved 105 into and out of the path of a moving part of said machine, an operating member actuated by the machine and connected with said counter actuating member, a sheet detecting member, a stop arm carried by said detecting member adapted to engage and arrest said operating member, and a cam upon said stop arm adapted to be engaged by said operating member for disengaging the detecting member from a sheet after the de- 110 tecting operation 115
